CLAIM

The ornamental design for a retractable key case, as shown and described.

DESCRIPTION

FIG. 1 is a top perspective view of a retractable key case showing my new design.

FIG. 2 is a bottom perspective view of the retractable key case shown in FIG. 1.

FIG. 3 is a top view of the retractable key case shown in FIG. 1.

FIG. 4 is a bottom view of the retractable key case shown in FIG. 1.

FIG. 5 is a front side view of the retractable key case shown in FIG. 1.

FIG. 6 is a back side view of the retractable key case shown in FIG. 1.

FIG. 7 is a right side view of the retractable key case shown in FIG. 1.

FIG. 8 is a left side view of the retractable key case shown in FIG. 1; and,

FIG. 9 is an alternate perspective view of the retractable key case shown in FIG. 1.

The broken lines depict portions of the retractable key case that form no part of the claimed design.
